Inventor:

Michael P. Fleming,
By Joshua H. Orr,
his Attorney.

UNITED STATES PATENT OFFICE.

MICHAEL P. FLEMING, OF CHICAGO, ILLINOIS.

SUPPLEMENTARY MATTRESS.

Specification of Letters Patent.

Patented Jan. 11, 1916.

1,167,989.

Application filed April 30, 1914. Serial No. 835,386.

To all whom it may concern:

Be it known that I, MICHAEL P. FLEMING, a citizen of the United States, and a resident of the city of Chicago, county of Cook, 5 and State of Illinois, have invented a certain new and useful Supplementary Mattress, of which the following is a specification.

My invention relates to a new and useful 10 mattress support, and the object of this invention is the production of a mattress support or supplementary mattress which is adapted to give stiffness to an ordinary mattress and prevent the latter from being 15 pressed into the springs of a bed thereby making small depressions which are uncomfortable to users of the mattress.

A further object is the production of a 20 simple and effective device of the character mentioned.

Other objects will appear hereinafter.

With these objects in view, the invention 25 consists in the combinations and arrangements of parts hereinafter described and claimed.

The invention will be best understood by 30 reference to the accompanying drawing forming a part of this specification, and in which,

Figure 1 is a view, in perspective, of a 35 supplementary mattress embodying my invention, showing one end slightly lowered to show the break therein, Fig. 2 is an enlarged transverse section of the same, and Fig. 3 is an enlarged fragmental longitudinal section.

The preferred form of construction as 40 illustrated in the accompanying drawing comprises a frame made up of rigid end members 4 and rigid side members 5 arranged on edge and secured together in any approved manner in rectangular form. Extending longitudinally between the ends 4 are ribs 6 of rigid material spaced apart and 45 secured to said ends by means of nails 7, or their equivalent passing through the ends and the covering to be mentioned hereinafter. Spaced apart and loosely mounted between the ribs 6 are short ribs 8. The 50 ribs 8 are also of rigid material and are held in position by means of the covering 9 and filling material 10 of the supplementary mattress. The covering 9 and filling material 10 are the ordinary substances for 55 like purposes in ordinary mattresses. The covering 9 is secured to the device by means

of stitchings 11 passing through said covering and the filling material 10. The stitchings 11 are similar to the ordinary stitchinging used in mattress-construction. 60

In smaller sizes of beds I prefer to make my supplementary mattress in one piece, but in larger sizes such as illustrated, I prefer to divide the supplementary mattress in two sections and hinge these sections together by 65 means of a portion 12 of the lower side of covering 9, see Figs. 1 and 3. This provides a means for doubling the mattress into smaller space and making it more convenient for handling. The ribs 6 being secured 70 to the frame of the device prevents the device from giving readily in small areas into a bed spring on which it may be used, and the ribs 8 provided for slight movement, since they are not secured to the ribs 6, permitting slight flexibility to the device so that in use, the device is yieldable and still firm enough to prevent the spring from being depressed unevenly under the weight of 75 a person. 80

While I have illustrated and described the preferred form of construction for carrying my invention into effect, this is capable of variation and modification without departing from the spirit of the invention. I, 85 therefore, do not wish to be limited to the precise details of construction set forth, but desire to avail myself of such variations and modifications as come within the scope of the appended claims. 90

Having described my invention what I claim as new and desire to secure by Letters Patent is:

1. A supplementary mattress comprising a rigid rectangular frame; parallel spaced 95 rigid ribs extending across and secured at their ends to said frame; a covering enveloping said frame; and filling material between said ribs in said covering, substantially as described. 100

2. A supplementary mattress comprising a rigid rectangular frame; a covering enveloping said frame; parallel spaced rigid ribs in and having their ends secured to said frame, the edges of said ribs engaging said 105 covering; and filling material between said ribs in said covering, substantially as described.

3. A supplementary mattress comprising a rigid rectangular frame; a covering enveloping said frame; parallel spaced rigid ribs in and having their ends secured to said 110

- frame, the edges of said ribs engaging said covering; short spaced parallel rigid ribs in said frame and between said first mentioned ribs and at right angles to the latter; and 5 filling material between said ribs in said covering, substantially as described.
4. A supplementary mattress comprising a rigid rectangular frame; a covering enveloping said frame; parallel spaced rigid ribs 10 in and having their ends secured to said frame, the edges of said ribs engaging said covering; short spaced parallel rigid ribs in said frame and between said first mentioned ribs and at right angles to the latter; filling 15 material between said ribs in said covering; and ties passing through said filling material and covering binding the latter against said ribs and said filling material, substantially as described.
- 20 5. A supplementary mattress comprising a rigid rectangular frame; a covering enveloping said frame; a plurality of spaced rigid ribs extending longitudinally of said frame; nails passing through said covering 25 and frame and into the ends of said ribs; a plurality of short spaced rigid ribs disposed transversely of said frame and positioned between said first mentioned ribs and the sides of said frame; filling material in said 30 covering and between said ribs and frame

portions; and ties through said filling material and covering binding the latter against said frame and ribs, substantially as described.

6. A supplementary mattress comprising 35 a rigid rectangular frame, a plurality of ribs arranged within said frame, certain of said ribs being rigidly connected to said frame and the remaining ribs being adapted for limited vertical movement, a filling arranged between said ribs and a covering enveloping said frame and filling, substantially as described.

7. A supplementary mattress comprising a rigid rectangular frame, parallel spaced 45 rigid ribs fixedly secured within said frame, short spaced parallel ribs arranged between the first mentioned ribs and at substantially right angles thereto, the last mentioned ribs having limited vertical movement, a filling 50 arranged between said ribs, and a covering, substantially as described.

In testimony whereof I have signed my name to this specification in the presence of two subscribing witnesses.

MICHAEL P. FLEMING.
